UNITED STATES PATENT OFFICE.

WILLIAM STUBBS, OF SHEFFIELD, ENGLAND.

APPARATUS FOR TWISTING METAL BARS.

1,395,617.

Specification of Letters Patent.

Patented Nov. 1, 1921.

Application filed June 3, 1920. Serial No. 386,181.

To all whom it may concern:

Be it known that I, WILLIAM STUBBS, a subject of the King of Great Britain and Ireland, residing at Sheffield, in the county 5 of York, England, have invented new and useful Improved Apparatus for Twisting Metal Bars, of which the following is a specification.

This invention relates to the twisting of 10 metal bars into spiral form (for any purpose for which twisted bars are used, or for making into drills, augers and the like tools) as the said bars issue from the rolls of a rolling mill, and the invention consists 15 in an improved method of and means for effecting the above named objects whereby a twisted bar and any remaining straight portion may be removed from the twisting dies without having to take any of the die 20 apparatus apart.

The preferred form of die which I provide according to this invention consists of a 25 number of flat cylindrical disks each of suitable thickness and each having a hole formed centrally in it, the opening at one side of which is of the same shape as the bar being rolled and the sides of the hole are so beveled and inclined that when the disks are 30 fixed in position against one another, the hole through them forms a spiral. The disks are inclosed in a box or cylinder, the front end of which forms a guide for the bar from the rolls to the disks.

My invention will be better understood 35 on reference to the accompanying drawings which illustrate one form of my invention.

Figure 1 is a side elevation of a twisting die holder placed in position in proximity to a pair of rolls.

40 Fig. 2 is a plan view, and

Fig. 3 is a back end view of same.

Fig. 4 is a longitudinal sectional view on 45 the line A B Fig. 2 showing a series of die members in position in the die holder.

Figs. 5, 6, 7 and 8 are views to an enlarged scale of the front faces of the four die members shown in Fig. 4 (i. e., the faces which are toward the rolls).

Figs. 5^a, 6^a, 7^a, and 8^a are views of the 50 reverse faces of the die members shown in Figs. 5 to 8.

Fig. 9 is a side view of one of the die members.

Fig. 10 is an end view of the dies assem-

bled and showing in full and dotted lines, 55 the contour of the openings in same.

Fig. 11 is a side elevation of the same.

The same letters refer to similar parts throughout the several views.

Referring to the drawings, a die holder 1 60 is shown arranged in operative position in proximity to a pair of rolls 2, 3, the front portion of the die holder being rounded at the top, in the form shown, as indicated at 4 and the rear portion being square shaped 65 as shown at 5. At the front end, the die holder 1 is provided with a projecting portion or tray 6 extending in between the rolls 2, 3, and adapted to receive the rolled bar which is required to be twisted as it 70 issues from the rolls. The die holder 1 is formed as a hollow cylinder having a uniform bore open at the rear end and closed at the front end except that the front end contains an opening 7 to admit the bar to 75 be twisted, this opening being continued as a passage 8 formed in a raised central portion 9 of the projection tray 6 and terminating in a splayed opening or slot 10 in the sloping front end 11 of the tray 6.

An opening or slot 12 is formed in the 80 top of the square portion 5 of the die holder 1 (Fig. 4) adapted to receive a locking plate 13 having lateral members 13¹ and 13² which bear against a tubular distance piece 85 14¹, which in turn again bears against the flanged end 14² of a tube 14 on the forward face of which are lugs 14³ engaging in slots 28² and 28³ in the face of the rearmost member of a series of die members 15, 16, 17, 18, 90 arranged in the die holder 1.

Four separate and independent die members are shown in the construction illustrated but it is to be understood that any desired number may be employed as may be 95 considered necessary in order to conveniently impart the desired twist to the bar under treatment. Though not illustrated it will be readily understood that washers can be placed between the die members when desired.

The die members 15 to 18 as shown in the drawings, are in the form of circular disks or plates adapted to be assembled together in one definite order, namely, in the order in 105 Fig. 4 with the disk 15 arranged at the rear end and the disk 18 at the front end of the said series. This order is determined by

the formation of the central hole provided in each of the said disks and which has to be traversed by the bar to be twisted.

Reference to Fig. 10 will show how the 5 respective openings in the dies are arranged in relation to each other, when set for the purpose of twisting a bar. The outlines shown on the figure are those on the rear or delivery sides of the respective disks and the 10 longitudinal center lines 1-1, 2-2, 3-3, 4-4 indicate the several angles of inclination through which the bar is twisted in its progress through the dies. As will be here- 15 after more fully explained, the bar is caused to assume the different angles of inclination between the delivery opening in one die and the delivery opening in the next, by means of beveled and inclined faces leading from one to the other.

20 Referring to Fig. 5 it will be seen that the front disk or die member 18 is provided with a central elongated opening 20 adapted to receive a flat bar to be twisted having a considerable width relatively to its thickness, this opening 20 being slightly inclined to the horizontal. The front edge 21 of the hole 20 first encountered by the bar coming from the rolls 2 and 3 is beveled or sloped in such a manner that, while the bar encoun- 25 ters a substantially horizontal edge of the hole in question, by the time the bar is issuing from the hole 20¹ at the rear side of the member 18 it is given a twist to the right to the extent shown in Fig. 5^a and as 30 indicated by the center line 1-1 (Fig. 10). The next die member which the bar has to pass through is that shown at 17 in Fig. 6, in which it will be seen that the lower left hand corner and the upper right hand corner 35 are cut away at 22 to permit of the entrance of the bar from disk 18, and inclined faces so formed in the disk 17 lead the bar through the opening 23 in the rear face where it assumes the inclination indicated by the cen- 40 ter 2-2 (Fig. 10). In like manner the configuration of the opening 24 in the front face of disk 16 (as shown in Fig. 7) enables the bar to pass from disk 17 and be guided through the back opening 25 in disk 16 (see 45 Fig. 7^a) when it will have the inclination indicated by the center line 3-3 (Fig. 10). The same principle of construction is adopted in the configuration of the front and rear openings 26 and 27 in disk 15, and as the bar 50 emerges from the opening 27 in the rear face, it assumes the inclination indicated by the center line 4-4 (Fig. 10).

By the time any given length of the bar has passed through the series of disks and 55 has finally issued from the back edges of the hole 27 of the rearmost disk 15, the said length of bar will have received a twist to the right through about an angle of 135°.

In order to assemble or pack the disks 15, 60 16, 17, 18 together in a compact or snug

manner, the disk 15 is provided on its front face with pins 28 and 28¹ adapted to be inserted in circumferential slots 29 and 29¹ formed in the adjacent disk 16, while the disk 16 is provided in a similar manner with 70 pins 30 and 30¹ adapted to be inserted in circumferential slots 31 and 31¹ formed in the adjacent disk 17; finally the disk 17 is provided on its front face with pins 32 and 32¹ adapted to be inserted in circumferential slots 33 and 33¹ formed in the foremost disk 18.

In addition to the above pins and slots, the foremost disk 18 has pins 34 and 34¹ on its front side which fit into holes 35 and 35¹ 80 formed in the end wall of the die holder. A keyway 36 is formed in each of the die disks 15, 16, 17, 18 and when the said disks are correctly assembled together in position to carry out a twisting operation, they are engaged by a key 37 hinged in any suitable manner to the die holder and passing through a longitudinal slot 38 formed in the top of the die holder 1, and thus firmly holding the series of die members 15, 16, 17, 18 90 in their correct operative position during the twisting operation.

In operation when it is desired to twist a bar, the bar is forced from the rolls 2, 3 into the opening 10 leading into the passage 95 8, through the opening 7 in the front end of the die holder 1, and thence through the twisting die consisting of the separate die members 18 to 15 whence the bar passes into the tubular guide 14 and so to the exterior 100 of the apparatus.

It will be understood that when the end of a bar being rolled has passed out of the rolls, the entire length of the bar can not be twisted since there is no power to push the 105 last portion through the twisting dies, and also the bar can not be readily pulled through the dies by hand when in their set position. At this stage of the operation, the key 37 is removed from the slots in the die members, and the bar is then pulled to draw the plain portion through the dies which can now be done inasmuch as the dies yield and permit of partial rotation (due to the endwise pull on the bar) until all the 110 longitudinal die openings are in the same horizontal plane (which will readily be understood on reference to Fig. 10) and consequently a clear passage is provided for the 115 plain portion of the bar.

When it is desired to reset the die members into position for twisting, the handle 14² on the guide 14 is given the necessary turning movement to enable the flange 14² 125 through the medium of the pins 14³ to turn the die member 15 until the pins 28 and 28¹ on its forward face traverse the length of the slots 29 and 29¹ in the adjacent member 16 which is then moved in like manner and so in turn are the whole series until further 130

movement is impossible, when the longitudinal axes of the die openings will have assumed the respective angles of inclination shown in Fig. 10, and all the keyways will be in line ready to receive the key 37.

Having now described my invention what I claim and desire to secure by Letters Patent is:—

An apparatus for twisting metal bars into spiral form, comprising a base, forming a die holder, a tubular guide at one end of said holder, a tray provided with a passage

at the other end of the holder for receiving the bar to be twisted, a plurality of flat cylindrical disks disposed within the holder, 15 each of said disks having a helical slot disposed centrally thereof, said slots forming a continuous helix, means for locking the disks against rotation, and means for partially rotating said disks.

In testimony whereof I have signed my name to this specification.

WILLIAM STUBBS.
